SIGNAL GENERATOR FOR SERVICING COLOR
AND MONOCHROME TELEVISION RECEIVING
OR TRANSMITTING EQUIPMENT

Rudolph L. Kuehn, Pasadena, Calif., assignor to Hycon
Mfg. Company, Pasadena, Calif., a corporation of Dela-
ware

Application April 30, 1956, Serial No. 41,264

Term of patent 14 years

(Cl. D26—1)

FIG. 1

FIG. 2

FIG. 4

FIG. 3

Figure 1 is a front perspective view of a signal generator for servicing color and monochrome television receiving or transmitting equipment, showing my new design;

Figure 2 is a front elevational view;

Figure 3 is a side elevational view showing the opposite side; and

Figure 4 is a rear elevational view thereof.

The drawing figures are hatched to indicate color contrast.

I claim:

The ornamental design for a signal generator for servicing color and monochrome television receiving or transmitting equipment, substantially as shown and described.
